Charles G. Hawley
Inventor.

UNITED STATES PATENT OFFICE.

CHARLES GILBERT HAWLEY, OF CHICAGO, ILLINOIS, ASSIGNOR TO LOCOMOTIVE FIRE-BOX COMPANY, OF CHICAGO, ILLINOIS, A CORPORATION OF DELAWARE.

LOCOMOTIVE FIRE BOX.

Application filed May 13, 1922. Serial No. 560,655.

To all whom it may concern:

Be it known that I, CHARLES GILBERT HAWLEY, a citizen of the United States, and a resident of Chicago, Cook County, Illinois, have invented certain new and useful Improvements in and for Locomotive Fire Boxes, of which the following is a specification.

My invention relates to locomotive boilers and has particular reference to improvements which are applicable to the Nicholson thermic siphon as disclosed in Patent No. 1,337,720 of April 20, 1920.

The nature of my invention and the form 15 of the typical locomotive boiler and firebox will be readily comprehended on reference to the accompanying drawings, in which Fig. 1 is a vertical longitudinal section of a locomotive firebox embodying my invention. Fig. 2 is a cross section thereof on the line 2—2 of Fig. 1. Fig. 3 is a plan view with a portion of the firebox crown sheet broken away to disclose the interior of the firebox. Fig. 4 is a diagrammatic view 20 showing how my novel thermic siphon is applied to the firebox. Fig. 5 is an enlarged horizontal section on either of the lines 5—5 of Figs. 1, 2 and 4. Fig. 6 is an enlarged vertical section on the line 6—6 of Fig. 1. Fig. 30 7 is an enlarged vertical section on the line 7—7 of Fig. 3. Fig. 8 illustrates a modification in the form of the upper rear end of the siphon.

The thermic siphon in itself and as generally known comprises a substantially triangular hollow water wall composed of the body portion 2 and the intake neck portion 3. The intake neck is placed in communication with the front water leg 4 of the boiler, while the top of the hollow body portion opens upward through the crown sheet 5 of the firebox 6. The body portion of the siphon being flat, is stayed by numerous stay-bolts 7. Likewise, all parts of the firebox crown sheet, side sheets, etc., are stayed by similar, but longer, stay-bolts 8, including the long radial or crown bolts which extend between the crown sheet 5 and the top of the firebox wrapper or shell 9.

As disclosed in the aforesaid Patent 50 1,337,720, the Nicholson thermic siphon is provided with wide top flanges, which are made to conform to the shape of the crown sheet of the firebox. Such flanges are weld-

ed to the crown sheet or otherwise attached 55 and more particularly are made to directly receive respective longitudinal rows of radial stay-bolts 8, the latter serving to safely support the siphon from the outside wrapper sheet of the firebox. In order to 60 install such a Nicholson siphon it is necessary first to cut a large opening in the crown sheet and then to fit the extensive flanges of the siphon to that opening and to weld the adjoining edges by the autogenous process.

The primary purposes of the invention are to avoid the somewhat difficult operations next above described, to very considerably lessen the cost of installing a 70 thermic siphon in a firebox, to reduce the preliminary disturbance of crown bolts in preparation for the installation of the siphon and to improve the stability and security of the structure as against all forces 75 tending to collapse the firebox and siphon.

With these objects in view, I entirely dispense with the well-known top flange of the thermic siphon and preferably with the flattening of the bulging portion of the 80 siphon at the top rear end. This is clearly indicated in Figs. 1 and 2, from which it will be seen that the sheet of metal composing the siphon is not flanged and that the bottom or bulging portion 2' of the siphon extends, with uniform dimensions, from the throat of the boiler to the crown sheet of the firebox. In brief, the top of the siphon is of the same shape as the lower intermediate portions and to install this simplified siphon it is only necessary to cut a narrow slot-like opening, of the same shape, 85 in the crown sheet 5 and thereupon the top of the siphon is lifted through the opening, the box then presenting the appearance indicated by dotted lines 10 in Fig. 4. Having so positioned the siphon and having first entered the neck 3 in the opening provided therefor in the throat sheet 4', the next step consists in welding the sides of the siphon 100 top directly to the adjoining edges 5' of the crown sheet opening, as well shown in Figs. 6 and 7. Top and bottom welds 11 and 11' are preferably employed for sake of security. After the siphon has been welded 105 into place the top edges are burned or otherwise cut off close down to the crown sheet.

The welds are so closely adjacent the adjoining rows of crown bolts 8 (see Figs. 3 and 6) as to remove all danger of separation at these points and the juncture of siphon 5 and crown sheet is fully as reliable as the flanged form proposed in the Nicholson patent; and the structure is much cheaper.

The upper rear end 2" of the siphon may be treated after either manner proposed in 10 Figs. 7 and 8. It may be lapped upon the top of the crown sheet as shown at 12 in Fig. 7, or may be shaped as shown in Fig. 8.

An advantage of the invention lies in the fact that the bulging portion 2' may continue 15 through the crown sheet as well shown at 13 in Fig. 3 without disturbing the adjoining stay-bolts in the crown sheet.

When the top welding of the siphon is dispensed with, as may safely be done, it is 20 entirely feasible to install a siphon without disturbing a single crown bolt. In other words, a very considerable saving in cost may be enjoyed as compared with the installation of the standard Nicholson thermic 25 siphon.

One of the marked advantages of the invention is that siphons of this improved form need not be built to exactly fit the firebox for which they are intended, but may 30 be fitted to a number of boxes of different sizes, it being obvious that very considerable tolerances are allowed by the extending upper edges and the long neck of the siphon.

The operation of the siphon is not different from that of the standard Nicholson thermic siphon, and therefore needs no detailed description herein.

Having thus described my invention, I 35 claim as new and desire to secure by Letters

40 Patent:

1. In combination with a locomotive fire box having a stay bolted crown sheet provided with an elongated opening therein, between adjacent rows of the stay bolts, a thermic siphon positioned in the fire box 45 and having a flangeless top end extending through said opening and beyond the top surface of the crown sheet and to which said flangeless top end of the siphon is automatically welded.

2. The method of equipping a locomotive firebox with a thermic siphon which consists in providing a siphon with a flangeless top end, forming an opening in the firebox crown sheet between adjacent rows of the stay bolts thereof just sufficient to accommodate said flangeless top end of the siphon, inserting said flangeless top end of the siphon through said opening so that it projects beyond the crown sheet, and welding said flangeless top end of the siphon to said crown sheet adjacent said opening.

3. The method of equipping a locomotive firebox with a thermic siphon which consists in providing a siphon with a flangeless top end, forming an opening in the firebox crown sheet between adjacent rows of the stay bolts thereof just sufficient to accommodate said flangeless top end of the siphon, inserting said flangeless top end of the siphon through said opening so that it projects beyond the crown sheet a greater distance than desired, welding said flangeless top end of the siphon to said crown sheet adjacent said opening and thereafter removing that portion of the flangeless top end of the siphon that projects beyond the crown sheet.

In testimony whereof, I have hereunto set my hand this 6th day of May, 1922.

CHARLES GILBERT HAWLEY.
